UNITED STATES PATENT OFFICE.

ANDREW BOSSHARDT, OF YORK, PENNSYLVANIA.

PENCIL-SHARPENER.

1,193,351.

Specification of Letters Patent.

Patented Aug. 1, 1916.

Application filed June 16, 1914. Serial No. 845,448.

To all whom it may concern:

Be it known that I, ANDREW BOSSHARDT, a citizen of the United States, residing at York, in the county of York, State of Pennsylvania, have invented certain new and useful Improvements in Pencil-Sharpener, and I do hereby declare the following to be a full, clear, and exact description of the invention, such as will enable others skilled in the art to which it appertains to make and use the same.

This invention relates to a pencil sharpener.

An object of the invention is to provide a very simple and small sharpener which may be attached to a pencil and left thereon in such position that it may be readily brought into use.

A further object of the invention is to provide means for clamping the device on the pencil.

A still further object of the invention is to provide means for releasing the clamp, the further movement of which will apply the cutting knives.

With these and other objects in view, such as will appear as the description progresses, my invention comprises the combination and arrangement of parts as herein set forth and subsequently claimed.

Referring to the drawing: Figure 1 is a side elevation of my device on a pencil in inoperative position. Fig. 2 is a similar view showing the same in operative position. Fig. 3 is a section on line 3-3 of Fig. 1. Fig. 4 is a detail with parts broken away showing the frame of the clamping fingers.

Referring to the drawing wherein like parts are indicated by like characters throughout the several views: My device comprises an annular casing having a vertical front wall 2 with a circular hole 3 formed therein. A tubular portion 4 extends rearwardly from this hole and spaced from this portion 4 and formed integrally with the periphery of the plate 2 is an annular plate 5. Rotatably mounted between the plate 5 and the tubular member 4 is a collar 6 having a cam face 7 on its forward end and an operating shank 8 on the rear end thereof which extends beyond the rear end of the plate 5 and is cut-away on its lower face, as at 9. On the rear end of this tubular member 4 is formed fingers 10 on which are located wedges 11 which fit into the cut-away portion 9 of the mem-

ber 6. An outwardly projecting portion 12 is formed on this collar 6 and a pin 13 projects from this portion and extends through an egee slot 14. Pivotal secured between the plate 5 and the tubular member 4 are a plurality of knives 15 having rearwardly extending arms 16 which normally rest on the cam face of the member 6. These knives 15 have longitudinally extending cutting edges 17 so that when the device is rotated and the knives are in contact with the point of a pencil the same will be sharpened.

Assuming that the device is in place on a pencil in inoperative position, the cut-away portion 9 of the member 6 bears against the wedges 11 on the fingers 10 and causes the fingers to grip the pencil. At this time the pin 13 is in the rearmost portion of the slot 14. The binding action between the member 6 and the wedges 11 is due to the fact that as the fingers 10 are resilient and the plate 5 is rigid, the riding up of the wedges on the cut-away portion 9 of the member 6 pushes the said fingers into engagement with the pencil.

When it is desired to sharpen the point of the pencil it is only necessary to grip the operating shank 8 of the member 6 and turn the same slightly, which causes the pin 13 to ride in the slot 14 and thus relieve the pressure between the wedges 11 and the cut-away portion 9 of the member 6, the entire device may then be moved to the end of the pencil, at which time the member 6 is turned farther and as it is turned the engagement of the pin 13 with the slot 14 causes the said member 6 to be drawn forwardly and the projections 16 to ride up on the cam face 7 so that the knives 15 will be thrown downwardly at an angle and the cutting edges thereof will contact with the portion of the pencil to be sharpened. The plate 5 is then gripped and rotated in the opposite direction to that in which the member 6 is rotated, which causes the knife edges 17 of the knives 15 to cut the material of the pencil and thus sharpen the same. After the pencil has been sharpened the operation may be reversed and the device clamped up on the upper end of the pencil out of the way but ready and convenient for the next operation.

From the foregoing description it may be seen that I have provided a very simple but small pencil sharpener which may be readily attached to a pencil and kept thereon, while

the same is being used so that it will be in a convenient position for use and will thus save a great deal of time in sharpening a pencil.

5 It is obvious that the number of knives may be changed as it is found desirable, and while I have described a particular construction of the device, I wish it to be understood that I do not wish to be limited to 10 that particular construction, for it is obvious that numerous changes may be made within the scope of the invention as defined by the claims.

What is claimed is:—

15 1. In combination, a body portion arranged to engage a pencil, means on said body portion to clamp the same to the pencil, knives pivotally mounted on the body portion, said clamping means being constructed and arranged to move the knives to 20 operative positions when operated to release the pencil.

2. In combination, a body portion constructed and arranged to engage a pencil, knives pivoted to said body portion, means on said body portion to grip the pencil and means to actuate said gripping means and on the reverse movement to move the knives to 25 operative positions.

Copies of this patent may be obtained for five cents each, by addressing the "Commissioner of Patents, Washington, D. C."

3. In combination, a body portion of an annular formation and having a tubular member extending therethrough, said tubular member having resilient fingers on the rear end thereof, wedges on the resilient fingers, a collar mounted in the body portion and having a cam face on its forward end, knives pivotally mounted in the body portion having extensions engaging the cam face, means for causing the collar to move the knives to operative positions when moved in one direction, and to actuate the resilient fingers to grip the fingers when moved in the other direction.

4. In combination, an annular body portion adapted to receive a pencil, knives pivotally mounted in said body portion to throw the knives into operative position, said means maintaining the knives in such position during the reverse movement of the body portion in one direction to cut the point of a pencil.

In testimony whereof, I affix my signature, in the presence of two witnesses.

ANDREW BOSSHARDT.
